(57) **CLAIM**

The ornamental design for a fishing hook and lure holder, as shown and described.

DESCRIPTION

FIG. 1 is a front and right side perspective view of a fishing hook and lure holder showing my new design;
FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is a rear view thereof showing connection of a fishing line to the small upper closed loop and connection of a shiny disc lure to the large lure holder open loop.

The broken lines showing a fishing line and a shiny disc lure in FIG. 8 are for illustration purposes and form no part of the claimed design.
